(57) **CLAIM**

The ornamental design for a connector for a breathing
conduit, as shown and described.

DESCRIPTION

FIG. 1 is a right, front perspective view of a connector for
a breathing conduit, which embodies our design.

FIG. 2 is a left, rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof.

FIG. 9 is a sectional view through the line 9-9 in FIG. 6; and,
FIG. 10 is a sectional view through the line 10-10 in FIG. 6.
The broken line portions in FIGS. 1-10 are for the purposes
of illustrating unclaimed portions that form no part of the
claimed design.
